UNITED STATES PATENT OFFICE.

FRANK E. STEBBINS, OF WASHINGTON, DISTRICT OF COLUMBIA.

ALCOVE SLEEPING-CAR.

1,119,466.

Specification of Letters Patent.

Patented Dec. 1, 1914.

Application filed July 27, 1910. Serial No. 574,109.

To all whom it may concern:

Be it known that I, FRANK E. STEBBINS, a citizen of the United States, residing at Washington, in the District of Columbia, have invented certain new and useful Improvements in Alcove Sleeping-Cars; and I do hereby declare the following to be a full, clear, and exact description of the invention, such as will enable others skilled in the art to which it appertains to make and use the same.

My invention generically relates to convertible sleeping and day cars of the alcove type, and specifically to certain improvements upon the constructions and arrangements disclosed in Letters Patent Nos. 897,314; 897,315; 897,797; and 897,798 of September 1, 1908.

The important objects or ends attained by the present improvements, as hereinafter set forth, are, to wit: the location of the upper berths nearer the floor of the car when in positions for use so they will be more easily accessible; the corresponding lowering of the lower berths so as to provide ample space between a lower and an upper berth; an improved construction of the upper berth whereby it can be manipulated with greater facility and caused to occupy a position when not in use adjacent the wall and roof of the car and not excessively project inwardly therefrom and overhang the seats as do the upper berths now commonly used in sleeping cars; improved means in part movable for shutting off the alcove spaces from the sections; and the production of a car having a wide unobstructed space in the top portion thereof, and which can quickly and easily be converted so as alternately to adapt it for day and night use.

The invention consists in certain novelties of construction and combination and arrangements of parts whereby the ends recited are attained.

The accompanying drawings illustrate several examples of the embodiment of the invention constructed according to the best modes of procedure I have so far devised for the purpose.

Figures 1 and 2 illustrate in plan a car embodying the invention. Fig. 3 is a cross section taken on line $x-x$ of Fig. 1 showing two upper berths in end elevations, one at the left raised and the other at the right lowered to a horizontal position, and the corresponding relative positions of two seats

one arranged for day use and the other lowered for use by night as part of a lower berth foundation. Fig. 4 is a cross section of Fig. 1 taken on line $y-y$ through two opposite alcove spaces. Fig. 5 is a view in elevation taken on line $z-z$ of Fig. 1 showing one section and an alcove arranged for night use with the berth curtain removed, and one section as it appears when arranged for use by day. Fig. 6 is a vertical section through a so-called section taken on line 2—2 of Fig. 1 showing one seat cushion and back upholstering arranged for day use and the other cushion and back upholstering lowered to form part of a lower berth foundation. Fig. 7 is a cross section of a car showing another embodiment of the invention, the dispositions of the upper berths relative to the car walls and roof when in raised positions being slightly different from those shown by Fig. 3. Fig. 8 is a cross section of a car showing another embodiment and a novel form of partition which is movable. Fig. 9 is a cross section of a car having an arched or Norman roof and embodying my invention in another form of construction.

Referring to Figs. 1 to 6, the numeral 1 designates the car floor; 2, 2, the vertical side walls with windows suitably spaced; 3, the raised deck of a well known construction; 4, 4, the two parts of the roof between the raised deck and the side walls; 5, 5, the longitudinal deck sills; and 6, the fixed arch rails extending across from one deck sill to the other.

The main portion of the interior space of the car is divided by seat backs or partitions 7, located at right angles to the side walls, and by fixed partitions 8 abutting the walls and in line with the seat backs or partitions 7, into a central passageway 9, sections 10, and alcove spaces 11 adjacent the sections. Each section is provided with two seats facing each other the upholstering of which can be adjusted to form a lower berth foundation for night use, and also with a hinged or pivoted upper berth of novel construction. Referring to the seats, 12 designates adjustable head rests; 13, movable back upholsterings; 14, movable seat cushions; 15, movable supports having notches or seats 16, 17 to receive and hold in proper relative positions the back upholstering and cushion of each seat, two supports 15 being provided for each seat one at the seat end

and one at the car wall; 18, horizontal rails at the car wall and on the seat end which hold the supports 15 in place and also serve to support the back upholsterings and cushions in horizontal positions when lowered; 19, fixed rails or supports on the floor below the front edges of the cushions; 20, seats or recesses in the rails; 22, legs secured to the front under surfaces of the cushion frames; 10 and 23 the fixed seat ends each provided with an arm rest.

In Fig. 6 at the right the back upholstering and cushion are shown arranged for day use, and at the left they are shown in 15 horizontal positions forming part of the lower berth foundation. The height of the front top surface of the edge of the rearwardly inclined cushion from the floor is about 18", and it is desirable to have the 20 distance from the floor to the top surfaces of the back upholstering and cushion when arranged to form a lower berth foundation about 14". Obviously, the parts are so constructed and arranged that this end can be 25 attained. The front edge of each cushion is raised withdrawing the legs from their seats, then the entire cushion is pulled forward and dropped so the rear edge of the cushion frame rests upon the rails 18 and 30 the legs support the front edge of the cushion from the floor. Each back upholstering is then turned forward, the supports 15 removed, and the back upholstering placed upon the rails 18 at the rear of the cushion. 35 The top surface of the lower berth foundation is thus in a plane some 4" lower than the top front surfaces of the cushions when in positions to be used as seats.

The hinged or pivoted upper berth in 40 each section is above and in line with the seats, and provision is made for dropping the berth to a horizontal position for use so that its under surface will lie in a plane about 50" or less from the car floor, where 45 by access to the same will be facilitated and its use rendered less objectionable. The upper berth is divided longitudinally into two parts so-called inner and outer, which parts are hinged together so the inner part 50 may occupy a substantially vertical position adjacent to the car wall when closed up, and the outer part, turned away from the lower part, occupy a position at an angle to the lower part and adjacent the roof or deck sill.

The number 24 designates the inner part of the upper berth; 25, the curved or rounded surface adjacent the car wall and window; 26, pivotal means or supports at each 60 end of the inner part, one member of each hinged or pivotal means being secured to or in the car wall and the other member to an end of the said inner part, the arrangement of the pivotal elements being such that 65 the body of the berth when turned down to

a horizontal position will preferably lie in a plane below the pivotal points and at the requisite distance from the car floor; 27, the outer part or leaf of the upper berth; 28, hinges by which the outer part is mov- 70 ably secured to the inner part; 29, cords or chains each secured at one end to the outer edge of the inner part of the berth and the opposite end secured to a spring drum 30 located on the wall within an alcove space, 75 the said chains or cords passing through and having bearings 31 in the partitions ad- jacent the plates and roof, as shown in Figs. 3 and 4; and 32, 33, respectively, are coöper- 80 ating bolts and sockets of any suitable or well known type located in or on the parti- tions and ends of the outer part of the up- per berth for locking the berth in a raised position. A flexible guard 34 is provided for the upper berth, its lower edge being se- 85 cured to the outer edge of the outer part or hinged leaf and its upper edge provided with a cord 35 the ends of which terminate in rings or hooks which engage hooks 36 upon the arch rails, which hooks are located 90 in line with curtain rod 37 secured to the arch rails above the alcove spaces. It will be observed that the outer part or leaf 27 of the upper berth is so hinged to the outer edge of the inner part 24 that a knuckle 95 joint is formed, that is, the leaf 27 cannot turn when in the same plane as the outer part over upon the inner part, but only away from it and beyond its outer edge, the side pieces at the ends of the inner and 100 outer parts abutting against each other, as will be obvious from an inspection of the figures of the drawings. To hold the outer part or leaf 27 in line with the inner part of the berth when lowered, sliding 105 bolts may be provided or the leaf may be held in place by cords or chains 38 one at each end of the leaf, the lower end of the cord being secured to the leaf and the free end provided with a ring or similar device 110 which engages a hook 36, as shown by Figs. 3 and 5. In the same figures it will be ob- 115 served that when the upper berth is folded up the flap or leaf 27 occupies a position back of the deck sill and at an angle to the substantially vertical inner or lower part of the berth, which dispositions of the parts provide a very wide open space in the top of the car adjacent to and below the deck sills.

The so-called inner part of the upper 120 berth consists of a panel of wood or metal of the length of the berth, but of less width than the entire berth when arranged for use, with end pieces integral therewith or secured thereto, the inner curved edge be- 125 ing extended to form a side piece, said edge being located adjacent to the car wall when the said inner part is in a vertical position. The so-called outer part or hinged leaf con- 130 sists of a panel of wood or metal with end

pieces and a side piece, the end and side pieces being substantially at right angles to the panel. The spring or other mattress (not shown) for the upper berth may be of any suitable construction, but preferably it is in two parts united and each respectively corresponding in shape to the outlines of the inner and outer parts of the berth or frame. The parts of the mattress may be detachably secured in position and the narrower part turned with the leaf to a position outside the panel of the inner part when the berth is swung up or raised.

The fixed partitions 8 in this example extend from the car walls outwardly as far as the deck sills, or a slight distance beyond them, and at night relatively narrow movable partitions 39 are placed upon the top outer edges of the seat backs to entirely shut off sections at their ends from alcove spaces.

Each alcove space is provided with a wall pocket 49 and storage cabinet 50 secured to the wall by hinges 51. The cabinet occupies a vertical position with its outer surface in line with the outer surfaces of the upper berths when closed, and when opened it is supported by cords 52. The cabinet covers the spring drums when closed.

In Figs. 7, 8 and 9 the constructions and arrangements of the seats are substantially the same as those hereinbefore described whereby they are convertible to form lower berth foundations in planes below the top surfaces of the cushions when arranged for day use. The upper berths and partitions, however, involve variations in construction and arrangement. Each upper berth is provided at the ends of the edge adjacent the car wall with metallic arms 53 extended the proper distance into the wall where they are pivoted by journals 54 (the same being accessible from the alcove spaces), the object being to allow the upper berth to turn or swing down to a horizontal position nearer the floor than would be the case with the pivotal points nearer the edge of the inner part of the upper berth.

In Fig. 7, the hinged leaf or outer part 27 of the berth when raised is disposed in a horizontal position back of the deck sill or apron, the outer surface of the leaf being at right angles to the outer vertical surface of the inner part of the berth, as shown. In Fig. 8 the leaf 27 has a curved or rounded outer surface 55, and the locking devices hold it adjacent the roof and below the deck sill. In Fig. 9 the hinged leaf or outer part 27 when the berth is raised occupies a recess 56 back of the apron or false deck sill 57, as clearly shown in the figure.

In each example the area of the exterior panel of the inner part of the berth when in a vertical position is approximately the same as the area of the window space, and also the same as the area of the car wall between

the floor and window sill, which correspondence of areas removes the topheavy appearance and oppressive effect occasioned by wide inwardly projecting, obliquely disposed, and overhanging upper berths.

70

In Figs. 7, 8 and 9 fixed posts 58 are present extending from the seat backs to the deck sills, such locations of the posts being preferable, as it leaves a relatively wide open space below the raised deck or arch rails and does not objectionably obstruct the view lengthwise of the interior of the car.

75

In Figs. 7 and 9 the partitions between the posts and the car wall are cut away for some distance above the seat backs to provide open spaces 59, which open spaces allow a wider view of the interior of the car than would be possible when partitions such as shown in Fig. 3 are present.

In Fig. 8 the open space 59 extends from the seat back to the leaf 27 of the upper berth when raised. To shut off or completely separate the alcove spaces from the sections by night movable partitions are provided each consisting of an inner leaf 60 and an outer leaf 61 united by hinges 62 which overlap the posts when adjusted upon the seat backs, the hinges aiding by their engagement with the posts to hold the partition in place.

85

The means for holding the upper berth shown by Figs. 7, 8 and 9 in raised and horizontal positions are substantially the same as those previously described. When the arch rails are located at the under surface of the deck roof, as in Fig. 8, the supports for the outer part 27 of an upper berth when lowered may consist of two rods 63 hinged at their lower ends to the outer part at its ends and provided with rings or similar devices at their free ends adapted to engage hooks or similar supports secured to the arch rails. The rods are turned down within the said outer part 27 of the berth when it is to be raised to the car wall and roof.

90

From the foregoing description taken in connection with the drawings it becomes obvious that the ends recited are effectively attained.

100

Owing to the fixed gage of the track, and the size of tunnels, bridges and cuts, limitations in the cross sectional area of passenger cars are correspondingly imposed. The problem is to make the available space within the car most comfortable for passengers. The improvements herein set forth are conducive to this end. The upper berth is located nearer the floor than in common practice whereby access to it is not difficult, and the lower berth is also lowered to secure ample head room and air space between the two berths. The construction and locations of the upper berths when raised, as herein described, secure a wide open space in the

105

110

115

120

125

130

top of the car not possible when the upper berths are closed to lie in oblique planes between the car walls and the deck sills. In practice the improvements may be embodied 5 in connection with cars constructed of wood or metal or of both in combination, and the seat frames, partitions, and upper berth frames may be of metal or other suitable material.

10 As is evident from an inspection of the drawings, the interior of the car with the improvements admits of effective artistic treatment, and to this end changes in details of construction, in the shapes and proportions of parts, and by additions may be made without constituting substantial departures.

What I claim is:

1. The combination in an alcove sleeping 20 car having a floor and walls, of fixed vertical seat backs located at right angles to the walls and dividing the floor area into a central passageway, sections and alcove spaces adjacent the walls, seat cushions and back 25 upholsterings in the sections adapted to form lower berths, upper berths hinged at the walls above and in line with the lower berths, fixed partitions in line with the seat backs and extending inwardly from the walls substantially 30 to the centers of the berths when lowered and closing the ends of the upper berths when raised, and means for entirely closing the ends of the upper berths from the alcove spaces when lowered to horizontal 35 positions consisting of movable partitions in connection with the tops of the seat backs and the fixed partitions.

2. The combination in an alcove sleeping 40 car having a floor and walls, of fixed vertical seat backs located at right angles to the walls and dividing the floor area into a central passageway, sections and alcove spaces adjacent the walls, seat cushions and back 45 upholsterings in the sections adapted to form lower berths, upper berths hinged at the walls above the lower berths, fixed partitions in line with the seat backs and extending inwardly from the walls and closing the ends of the upper berths when raised, fixed 50 posts in connection with the seat backs and substantially at the centers of the upper berths when lowered, the relation of the posts to the fixed partitions being such that an open space is provided between a post 55 and a partition, and movable partitions in connection with the seat backs and posts for closing the openings between the fixed partitions and the posts and also shutting off the ends of the upper berths when lowered 60 from the alcove spaces.

3. The combination in an alcove sleeping 65 car having a floor and walls, of fixed vertical seat backs located at right angles to the walls and dividing the floor area into a central passageway, sections and alcove spaces

adjacent the walls, seat cushions and back upholsterings in the sections adapted to form lower berths, upper berths hinged at the walls above the lower berths, fixed partitions in line with the seat backs and extending inwardly from the walls and closing the ends of the upper berths when raised, fixed 70 posts in connection with the seat backs and substantially at the centers of the upper berths when lowered, the relation of the posts to the fixed partitions being such that an open space is provided between a post 75 and a partition, and movable partitions each consisting of two leaves hinged together in connection with the seat backs and posts for closing the openings between the fixed partitions and the posts and also shutting off the ends of the upper berths when lowered 80 from the alcove spaces.

4. The combination with a sleeping car 85 section, of an upper pivoted berth comprised of inner and outer panels hinged together, the inner panel when the berth is raised occupying a position substantially parallel with the car wall, said berth being 90 so pivoted that when turned to a horizontal position it will lie in a plane below the pivotal points, and seat cushions and back upholsterings adapted to be bodily lowered from the positions they occupy by day and 95 supported to form a lower berth below the plane of the seat cushions when arranged for use as seats.

5. The combination with a sleeping car 100 section, of an upper berth with a leaf hinged to its outer edge, said berth and leaf being adapted to occupy substantially vertical and angular positions when turned up, said berth being pivoted at the car wall so it may swing to a horizontal position below the 105 pivotal points, and seat cushions and back upholsterings adapted to be bodily lowered below the plane of the cushions when arranged for day use and form a lower berth.

6. The combination with a car, of an upper berth comprised of inner and outer panels hinged together, the inner panel occupying a position substantially parallel with the wall when raised and the outer panel turned outwardly being located adjacent the roof, said inner panel being provided with pivotal means so disposed that when the berth is turned to a horizontal position it will lie in a plane below the position occupied by its inner edge when raised; 110 movable seat cushions and back upholsterings below said upper berth which can bodily be lowered below the plane of the cushions as arranged for day use; and means for supporting the cushions and back upholsterings in their lowered positions, whereby the upper berth may easily be accessible and sufficient head room and air space be provided between the upper and lower berths. 115 120 125 130

7. The combination with a sleeping car section having seat backs and seat ends, of cleats on the seat ends and upon the wall, cushions with supports secured at their front under surfaces, supports upon the floor, removable back upholsterings, and means for retaining the cushions and back upholsterings in their proper relative positions by day; the cleats being located some distance below the cushions and adapted to support the cushions and back upholsterings in a bodily lowered position by night to form a lower berth foundation.

8. The combination with a sleeping car section having seat backs and seat ends, of two back upholsterings, two seat cushions with legs, supports with means to retain the legs, cleats on the seat ends and wall or like supports, and movable supports with notches or seats, whereby the cushions and back upholsterings may be properly supported for day use and bodily lowered to form a lower berth.

9. The combination with a car having a wall and roof, of an upper berth formed of longitudinal sections or parts hinged together, and means for pivotally supporting said berth adjacent the car wall, the arrangement being such that when folded up the inner section will occupy a position substantially parallel with the wall and the outer portion or front edge part will occupy a position adjacent the roof of the car and project outside the inner section.

10. The combination with a car having a wall and roof, of an upper berth formed of longitudinal sections or parts hinged together, and means for pivotally supporting said berth adjacent the car wall; the arrangement being such that when folded up the inner section will occupy a position substantially parallel with the car wall, and the outer or front edge portion will occupy a position adjacent the roof of the car and project outside the inner section; means being provided for locking said front edge or part in its raised position.

11. The combination with a car having a wall and roof, of an upper berth made in two parts, one wider than the other, and each of the length of the berth, and hinged together; and means for pivotally supporting the berth adjacent the wall; the arrangement being such that the wider part shall fold to a substantially vertical position and the narrow part occupy a position at an angle to the wider part and outside of it and beneath the roof.

12. The combination with a car having a wall, roof and partitions, of an upper berth pivoted between the partitions, said berth being longitudinally divided and the parts hinged together, the inner part of the berth when folded up being in a substantially vertical position and the outer part or leaf an-

gularly disposed to the inner part and extending outside the same, and both parts being bounded by the partitions at their ends.

13. The combination with a car having a wall and roof, of an upper berth composed of a plurality of panels or pieces and hinged together, the inner panel being pivoted to the car and the outer piece hinged so it can turn away from the inner panel; said berth when turned up having the inner panel substantially vertical and the outer piece lying turned out from the plane of the inner panel, and means for holding the parts of the berth in their raised angular and lowered horizontal positions.

14. The combination with a car having a wall and roof, of a berth comprised of a plurality of parts, inner and outer, of substantially the length of the berth and hinged together, the inner part having arms pivoted at the wall by pivots or hinges so located that when lowered the body of the berth will lie in a horizontal plane below the pivotal points, and when swung up the inner part will be in a substantially vertical plane and above the pivotal points, and the outer part turned out at an angle to the inner part will lie below the roof.

15. The combination with a car having arch rails and supporting devices in connection therewith, of a pivoted upper berth having a main inner part provided with a leaf hinged to turn only from a position in the same plane as the main panel of the berth to a position outside the said main panel, and supports secured to the leaf of the berth and adapted to engage the said supporting devices in connection with the arch rails whereby the leaf is held in line with the main part of the berth.

16. The combination with a car, of a pivoted upper berth having an inner part and a hinged leaf, cords or chains secured to the inner part and to the car for holding the inner part in a horizontal position when lowered, and means for supporting the hinged leaf in line with the inner part, said leaf in its raised position being located outside the inner part.

17. The combination with a car, of a pivoted upper berth comprising an inner part and a leaf hinged to said inner part so as to form a knuckle joint, means for holding the leaf in line with the inner part when the berth is lowered to a horizontal position for use, and cords or chains connected to the berth and to spring drums for holding the berth in its lowered horizontal position, the leaf being turned away from and located outside the panel of the inner part when the berth is raised.

18. The combination with a car, of an upper berth comprising an inner part with a panel of the length of the berth and pivoted at its rear edge to the car, and an outer part

hinged to the inner part so said outer part can be turned to a position at right angles to the panel of the inner part; said berth when swung up occupying substantially vertical and horizontal positions adjacent the wall and the roof of the car, the said outer part being turned away from and disposed substantially at right angles to the inner part, and means for holding said inner and outer parts in their said relative positions when raised.

19. The combination with a car, of an upper berth comprising a panel hinged at its inner edge so as to lie adjacent the car wall, and a front part pivoted to the panel portion to increase the width of the berth and which front part can be shifted or turned away from the panel so the latter can fold to a substantially vertical position below the roof; and means for supporting the front part from the roof when the berth is in use.

20. The combination with a car having a wall, roof and depending deck sill or apron, of an upper berth longitudinally divided into a plurality of parts hinged together, the front edge piece swinging outwardly from the plane of the inner piece and when the berth is folded up occupying a position back of the deck sill or apron and at an angle to the and outside the inner piece.

21. The combination with a car having a wall, roof and deck sill or apron, of an upper berth comprised of a plurality of longitudinal parts united, as by hinges, and said berth pivoted at the wall; the inner part when folded up being substantially vertical and the outer part lying at an angle to the

plane of the inner part and with the outer edge adjacent the deck sill or apron, whereby a continuous surface is presented between the deck sill or apron and the top of the inner part of the berth.

22. The combination with a car having a wall and roof, of an upper berth formed of longitudinal sections or parts hinged together, each of said sections or parts having end pieces and means for pivotally supporting said berth adjacent the car wall, the arrangement being such that when folded up the inner part will occupy a position substantially parallel with the wall, and the front part or leaf will occupy a substantially horizontal position outside the inner part and adjacent the roof.

23. The combination with a car having arch rails extending across the car from side to side of the roof, of sections with an upper berth in each section hinged with one edge at the car wall, each upper berth being comprised of a plurality of parts longitudinally divided and hinged together, the outer part or leaf of the berth when raised lying outside the inner part and when the berth is lowered being in line with the inner part, and means in connection with the leaf and arch rails for supporting the said leaf in a horizontal position.

In testimony whereof I affix my signature, in the presence of two witnesses.

FRANK E. STEBBINS.
